3 Claims. (Cl. 250—41.9)

The present invention relates to mass analyzing or resolving systems and, more particularly, to improvements in double-focussing mass spectrometers.

Double-focussing mass spectrometers are well known in the art and have, for example, been described in "Mass Spectrometry and Its Applications to Organic Chemistry," by J. H. Beynon, Elsevier Publishing Company and D. Van Nostrand Company, Inc., 1960, Chapter I, Section 1.7; "Zeitschrift für Physik," 98, 1934, page 786, Mattauch and Herzog; and U.S. Patent 2,851,608, "Mass Spectrometer," September 9, 1958, by Dr. C. F. Robinson. Briefly, a double-focussing mass spectrometer comprises means for causing the release of particles in ionized form from the substance under investigation, an electrostatic ion deflector, a magnetic ion deflector and suitable ion sensing means.

It is also known in the art that some of the ions in the ion beam produced in this type of apparatus from the substance being investigated do not follow the "optical" axis of the spectrometer but emanate from the substance at various angles to this axis. The ions that are able to reach the recording or sensing medium of the spectrometer despite their angular deviation from so-called angular images. In addition, it is known that even those ions that travel along the optical axis leave the substance under investigation at different velocities and, as a result, form on the recording or sensing medium of the spectrometer so-called velocity images.

In theory, a mass spectrometer can be built in which the velocity and angular images coincide on the ion recording or sensing means. In practice, however, it has been found that this goal is difficult to realize with conventional mass spectrometer apparatus. In consequence, the resulting mass spectra contain undesirably broadened images for one and the same substance, of which the first order angular images and the first order velocity images may be particularly bothersome, especially in cases, such as isotope work, where the spectrum lines of the substance components are rather closely spaced.

In the past, various mechanical adjustments have been proposed and effected in an attempt to reduce the above-mentioned image broadening. However, the adjustments so far proposed are generally inconvenient and do not ordinarily yield the desired result.

The subject invention overcomes these disadvantages by providing convenient and effective means for bringing at least first order angular and velocity images into substantial coincidence with each other and with the photographic plate or other ion detecting means of the mass spectrometer. The invention stems from the discovery that angular and velocity images will move into coincidence with each other when the potential with respect to ground of at least one of the two deflector plates of the electrostatic deflector assembly employed in double-focussing mass spectrometers is varied, or when the potential at one deflector plate is varied in one sense and the potential at the other deflector plate in the opposite sense. We have discovered that these potential variations will bring about a coincidence between angular and velocity images, particularly those of the first order. Neverthe-

2

less, the point of coincidence of these angular and velocity images is not necessarily located at the photographic plate or other ion sensing means employed in double-focussing mass spectrometers. There exists, therefore, a need for a means which will cause the joint movement of the substantially coinciding angular and velocity images onto the photographic plate or ion sensing means. We have found that an electrostatic lens or lens system combined with a source of variable potential constitutes such a means. The electrostatic lens has the property of moving angular and velocity images at similar speeds when the lens potential is varied. In this fashion, it is possible to move the angular and velocity images, which have been brought into substantial coincidence in the manner mentioned above, toward and onto the ion recording medium or sensing means. This is the case even if the lens adjustment should cause a slightly different movement of the angular and velocity images, since such a difference can be corrected by readjustment of the deflector plate potentials.

In accordance with a preferred embodiment of the invention, the mass spectrometer apparatus comprises means for sensing ions and deflector means including an electrostatic deflector having two spaced deflector plates. The apparatus includes means for applying to one of the deflector plates a first potential with respect to ground and to the other deflector plate a second potential with respect to ground. The apparatus also has means for producing from the substances under investigation ions that form angular and velocity images in the vicinity of the ion sensing means.

According to the invention, the mass spectrometer apparatus includes means for varying at least one of the above-mentioned first and second potentials to move the angular and velocity images substantially into coincidence with each other, and an adjustable electrostatic lens means for moving the substantially coinciding angular and velocity images into coincidence with the photographic plate or other ion sensing means.

Apart from a photographic plate or film, the above-mentioned means for sensing ions may comprise electrical sensing means. The first and second potential of the electrostatic deflector plates may be supplied by one high voltage supply that has an impedance or resistor with grounded center tap associated therewith. The means for varying at least one of the first and second deflector plate potentials may comprise a variable voltage source that is connected to add its output voltage to the plate-to-ground potential of one of the plates.

More conveniently, the potential variation taught herein may be effected by varying the impedance or resistance in at least one leg of the above-mentioned center-grounded impedance or resistance. A particularly advantageous adjustment is also provided by means which subtract a variable voltage from the plate-to-ground potential of one of the deflector plates, while adding voltages to the plate-to-ground potential of the other deflector plate. In a preferred embodiment of the invention, this effect is brought about by connecting across the above-mentioned

high voltage supply a potentiometer with a grounded movable arm. The plates are connected to the stationary terminals of this potentiometer. If the movable arm of the potentiometer is located so as to divide the potentiometer into two resistor sections of equal value, there are equal, though oppositely poled, plate-to-ground potentials at the deflector plates. If the potentiometer arm is moved from its center position, the plate-to-ground potentials at the two deflector plates vary in opposite senses. In addition, the apparatus includes electrostatic lens means for moving the substantially coinciding angular and velocity images into substantial coincidence with the ion recording or sensing means.

The invention will become more readily apparent from the following detailed description of a prior art system and of embodiments of the invention, illustrated by way of example in the accompanying drawings, in which:

FIG. 1 is a diagrammatic side view of a prior-art mass spectrometer;

FIG. 2 shows a detail of the apparatus shown in FIG. 1 with ion trajectories; and

FIG. 3 is a diagrammatic side view of an apparatus embodying the invention.

The apparatus shown in FIG. 1 will be recognized by those skilled in the art as being a double-focusing mass spectrometer of the so-called Mattauch type as described, for example, in the initially mentioned literature. This apparatus has a pair of spark electrodes 11 and 12 connected to a conventional Tesla transformer 14. It also includes an apertured accelerating electrode 15 which is connected to the movable arm 16 of a potentiometer 17. A high voltage supply 18 is connected across the potentiometer 17. One terminal 20 of the high voltage supply 18 is grounded and the other terminal 21 is connected to the Tesla transformer 14 so that the accelerating electrode 15 is suitably biased with respect to the spark electrodes 11 and 12.

The apparatus shown in FIG. 1 further includes the conventional electrostatic deflector 23 composed of deflector plates 24 and 25 and the conventional magnetic deflector 26 composed of a pair of magnetic pole pieces only one of which is shown in FIG. 1 at 27. Grounded apertured electrodes 29 and 30 are located between accelerating electrode 15 and deflector 23, and grounded apertured electrodes 31 and 32 are located between electrostatic deflector 23 and magnetic deflector 26 in a manner well known in the art. An ion sensing means 34, such as a photographic plate, is located at the magnetic deflector 26 for producing the mass spectrum. If desired, other ion sensing means, such as Faraday cups or electron multiplier assemblies may be used in lieu of plate 34. The deflector plates 24 and 25 of the electrostatic deflector 23 are connected, respectively, to terminals 35 and 36 of a deflecting voltage supply 37. A pair of series-connected resistors 38 and 39 is connected across terminals 35 and 36. The junction 40 between resistors 38 and 39 is grounded.

The structure shown in FIG. 1 and its operation are well known in the art. Initially, a sample 41 of the substance to be tested is placed onto one of the spark electrodes 11 and 12. The system is then evacuated. Neither the vacuum envelope nor the evacuation apparatus have been shown in FIG. 1, as these means are well known in the art. During operation of the apparatus of FIG. 1, the potential supplied by Tesla transformer 14 will generate an electric spark 42 between electrodes 11 and 12 which will cause the sample 41 to release material particles in ionized form. Under the influence of accelerating electrode 15, many of these ions are caused to travel in the general direction of the optical axis 44 of the mass spectrometer. However, it is well known that not all ions travel exactly along the optical axis 44. This fact has been schematically illustrated in FIG. 2 which shows an arrow 46 representing ions that travel from the sample 41 along the optical axis 44 at a first velocity, an arrow 47 representing ions that travel along the optical axis 44 at a second, different velocity, and an arrow 48 representing ions that travel from sample 41 at an angle α with respect to the optical axis 44. Ions of the type represented by arrows 46 and 47 form so-called velocity images, while ions of the type represented by arrow 48 form so-called angular images.

For the purpose of illustration, a velocity image has been shown in FIG. 1 at 58 and angular image at 59. The images 58 and 59 neither coincide with each other nor with the emulsion surface of photographic plate 34. The visible images on the photographic plate are thus unduly broad. In the interest of a precise analysis, it

is, of course, highly desirable that the velocity and angular images meet each other substantially on the photographic plate 34.

FIG. 3 shows means for realizing this desideratum.

- 5 The basic parts of the mass spectrometer illustrated in FIG. 3 have been shown in FIG. 1, so that the reference numerals used in FIG. 1 are employed in FIG. 3 for denoting these parts. According to the invention in the embodiment shown in FIG. 3, the resistors 38 and 39 of the apparatus of FIG. 1 are replaced by a potentiometer 60 that is connected between terminals 35 and 36 of deflecting voltage supply 37 and has a grounded movable arm 62. If the movable arm 62 is located in its center position so that it divides the potentiometer 60 into two resistor sections of equal resistance, the effect of the potentiometer 60 is the same as of the resistors 38 and 39 in FIG. 1. In this case, the velocity and angular images normally fail to coincide with each other. We have discovered that these images move by different distances 10 if an offset voltage ΔV is introduced at the electrical midpoint between deflecting sectors 24 and 25, as has been mentioned above. In FIG. 3, this introduction of offset voltage ΔV is conveniently effected by moving the arm 62 of potentiometer 60. This is illustrated in FIG. 20 3 by dotted arm 62'. In this manner, one of the plates 24 and 25 will experience an increase of ΔV in its potential with respect to ground, while the other plate will experience a decrease of ΔV in its potential with respect to ground. By adjusting these voltages ΔV , the velocity 30 and angular images can be brought into mutual coincidence. However, this point of coincidence is not necessarily located on plate 34. A further adjustment is, therefore, desirable which moves this point of coincidence onto plate 34. In the embodiment in FIG. 3, 35 this further adjustment is effected by an electric lens 65 which is located between deflector systems 23 and 26 and is composed of a pair of grounded, apertured electrodes 66 and 67 having a further apertured electrode 68 disposed therebetween. The lens electrode 68 is connected to the movable arm 70 of a unilaterally grounded potentiometer 71. A lens bias voltage source 72 that supplies a direct-current voltage of, say, one hundred volts is connected to potentiometer 71. If desired, the lens 65 may also be of a conventional cylindrical type (not shown). Adjustment of potentiometer 71 will cause movement of the velocity and angular images relative to plate 34. In this manner, it is not only possible to bring the velocity and angular images into mutual coincidence, but also substantially into coincidence on plate 34. The amount of movement of the angular image in response to adjustment of potentiometer 71 will usually be somewhat different from the amount of simultaneous movement of the velocity image. However, this difference can largely be corrected by adjustment 45 of potentiometer 60. Since electrostatic lens systems are of the electrostatically positive type, it is advisable to locate the spark electrodes 11 and 12 slightly farther away from the electrostatic deflector 23 than in the prior art apparatus illustrated in FIG. 1. The resulting 50 coincidence of the above-mentioned images 59 and 58 on plate 34 is apparent from FIG. 3.

It will now be recognized that the invention provides a particularly advantageous, convenient and effective means for obtaining high-quality operation of mass spectrometers.

Various modifications within the scope of the invention will be apparent to those skilled in the art.

We claim:

1. In a double-focusing mass spectrometer having in 70 serial arrangement an ion source, including means for producing ions that form first order angular and velocity images, an electrostatic analyzing sector adjacent the ion source, the electrostatic sector having two spaced deflector plates, a magnetic analyzing sector, a drift space between the electrostatic and magnetic sectors, and 75

means for sensing ions, the improvement comprising means for applying a first potential with respect to ground to one of the deflector plates of the electrostatic analyzing sector and a second potential with respect to the ground to the other deflector plates of the electrostatic analyzing sector, means for varying at least one of the first and second potentials to move the angular and velocity images substantially into coincidence with each other in the vicinity of the ion sensing means, and adjustable electrostatic lens means interposed in the drift space between the electrostatic analyzing sector and the magnetic analyzing sector for moving the substantially coinciding angular and velocity images onto the ion sensing means.

2. In a double-focusing mass spectrometer having in serial arrangement a source of ions of substances to be investigated including means for producing from said substances ions that form images including a primary image, first order angular images and first order velocity images, deflector means including an electrostatic deflector having two spaced deflector plates located adjacent the source of ions and a magnetostatic deflector, a drift space between the electrostatic and magnetostatic deflectors and a collector for the ions, the improvement comprising means for applying to one of the deflector plates of the electrostatic deflector a first potential with respect to ground and to the other deflector plate of the electrostatic deflector a second potential with respect to ground, means for reducing one of the first and second potentials and for increasing the other of the first and second potentials to move the angular and velocity images substantially into coincidence with each other in the vicinity of the collector, and an adjustable electrostatic lens located in the drift space between the electrostatic and magnetostatic deflector for moving the substantially coinciding angular and velocity images into coincidence with the primary image at the collector.

3. In a Mattauch-Herzog type of double-focusing mass spectrometer comprising an electrostatic ion deflector having two spaced deflector plates, a magnetic ion deflector, means for sensing ions traversing a path through the electrostatic and magnetic ion deflectors and an ion source for producing ions that form images including a primary image, first order angular images, and first order velocity images in the vicinity of the ion-sensing means, the improvement comprising a potentiometer having a grounded movable arm connected to the deflector plates of the electrostatic ion deflector, a deflection voltage supply connected across the potentiometer, an electrostatic lens located between the electrostatic ion deflector and magnetic ion deflector, and means for applying a variable electric potential to the electrostatic lens whereby adjustment of the potentiometer arm moves the angular and velocity images substantially into coincidence with each other and adjustment of the variable electric potential applied to the lens moves the substantially coinciding angular and velocity images into coincidence with the primary image at the ion sensing means.
